END BAR SUPPORT FOR TENSION TYPE
FRAMELESS WINDOW SCREENS

David Jordan Rust and Jack H. Jensen, San Leandro, Calif., assignors to Ry-Lock Company, Ltd., San Leandro, Calif., a corporation of California

Original application January 13, 1948, Serial No. 2,077. Divided and this application November 28, 1949, Serial No. 129,842

1 Claim. (Cl. 160—327)

1

The present invention relates to, and it is an object to provide, a novel, end bar support for a tension type frameless window screen which includes transverse end bars adapted to be secured to a window frame with the screen under tension between said bars.

Another object of the invention is to provide an end bar support, for the purpose described, which includes saddle brackets mounted on opposite sides of the window frame and facing lengthwise of but away from the screen; the end bar projecting at opposite ends beyond the adjacent edges of the screen and resting in the saddles of corresponding brackets.

A further object of the invention is to provide an end bar support which is especially adapted, but not limited, for use in cooperation with the end bar at the top of a tension type frameless window screen, wherein the screen tensioning means engages the end bar at the bottom of the screen.

An additional object of the invention is to provide an end bar support which is capable of withstanding relatively great tension on the screen; the end bar which cooperates with the support being effectively held against escape from said support when the screen is under tension, and being formed to minimize outward strain on the saddle brackets which are included in the support.

It is also an object of the invention to provide an end bar support which is designed for ease and economy of manufacture, and ready installation on a window frame.

Still another object of the invention is to provide a practical and reliable end bar support for a tension type frameless window screen.

This invention is a division of application, Serial No. 2077, filed January 13, 1948, on Window Screen, which issued on March 14, 1950, as U. S. Patent Number 2,500,470.

The above objects are accomplished by means of such structure and relative arrangement of parts as will fully appear by a perusal of the following specification and claims.

In the drawings:

Fig. 1 is a front elevation of a tension type frameless window screen embodying the present invention.

Fig. 2 is a side or edge elevation of the same, partly in section.

Referring now more particularly to the characters of reference on the drawings, the invention is embodied in a tension type frameless window screen which includes a rectangular section 1 of wire cloth having affixed to the corresponding

2

edges thereof a transverse top bar and a transverse bottom bar, indicated generally at 2 and 3 respectively.

The section 1 of wire cloth, with the bars 2 and 3 affixed thereto, overlies the opening 4 of a window frame or casement, indicated generally at 5; such casement including side flanges 6.

The top bar 2 and bottom bar 3 project at the ends, as at 7, beyond the corresponding side edges of the section 1 of wire cloth; the projecting ends 7 of the top bar 2 resting in saddle brackets 8, hereinafter described in greater detail, affixed to the side flanges 6 of the casement 5.

The projecting ends 7 of the bottom bar are normally engaged, from above and also on the front, by screen tensioning turns 9 affixed to the corresponding side flanges 6 and including eccentric cams 10 which bear downward, forcefully, on the upper edge of said bottom bar 3 when the turns 9 extend downward in lapping relation thereto. In this manner the section 1 of wire cloth is placed under relatively great tension, and at the same time the transverse bottom bar 3 is held against outward displacement from the casement 5.

At its upper edge the section 1 of wire cloth is secured to the top bar 2 in the following manner:

The top bar 2 is of substantial height, and includes a longitudinal foot 11 along its upper edge, with a longitudinal, outwardly extending offset 12 immediately below such foot, whereby the face of said top bar 2 is offset outwardly with respect to the foot 11. The longitudinal, lower edge portion of the top bar 2 is bent inwardly and back toward the offset 12 whereby to form a holding or clamping flange 13. The upper edge portion of the screen extends up the back side of the flange 12, passes over the upper edge of the latter, and thence extends downward between said clamping flange and the front portion of the bar; this latter portion of the screen being doubled back upon itself, as shown. With this assembly, the section 1 and the top bar 2 are effectively secured together against accidental separation.

By bending the lower portion of the top bar 2 inwardly and back toward the offset 12, as described above, the lower edge of said top bar 2 is rounded, as at 14.

The saddle brackets 8 each include a flat, perpendicular bracket plate 15 vertically adjustably secured to the side flange 6 by a headed screw 16 which extends through a vertical slot 17 in the bracket plate 15, and thence is threaded into said flange. At its lower end each bracket plate 15 is outturned, as at 18, to form a finger tab,

while the upper end of each bracket plate curves outwardly and upwardly to form a saddle 19 which faces upwardly.

The rounded lower edge portions 14 of the projecting ends 7 of the top bar 2 rest in substantially matching relation in the saddles 19; the tension imparted to section 1 of wire cloth by the cam turns 9 effectively holding said end portions 7 against accidental escape from said saddles.

The longitudinal foot 11 bearing against the top flange 20 of the casement 5 above the window opening 4 prevents or minimizes outward strain on the saddles 19 resulting from downward pull on the holding or clamping flange 13 by the highly tensioned section 1 wire cloth. This is a valuable feature, and assures that the saddle brackets 8 will not be sprung outwardly under, or by reason of, the tension on the section 1 of wire cloth.

As the bracket plates 15 are vertically adjustable, the screws 16 can be threaded into the side flanges 6 without the necessity of great accuracy with respect to vertical position, and the saddle brackets 8 can be readily initially adjusted up and down on said screws. Additionally, after some use, during which time the section 1 of wire cloth may stretch slightly lengthwise, the saddle brackets 8 may be vertically adjusted to compensate for such stretch; i. e. adjusted so that the cam turns 9, when swung to working position, will properly tension the screen.

The lower edge of the section 1 of wire cloth is affixed to the bottom bar 3 in the same manner, as above described, as the top bar is attached.

The described support for the top bar 2, in cooperation with the projecting ends of said bar, provides a very effective and reliable structure for anchoring the upper end of a tension type frameless window screen to a window frame or casement.

From the foregoing description it will be readily seen that there has been produced such a device as substantially fulfills the objects of the invention, as set forth herein.

While this specification sets forth in detail the present and preferred construction of the device, still in practice such deviations from

such detail may be resorted to as do not form a departure from the spirit of the invention, as defined by the appended claim.

Having thus described the invention, the following is claimed as new and useful and upon which Letters Patent are desired:

In combination with a window casement which includes a top flange above the window opening, a bottom flange below the window opening, and side flanges between the top and bottom flanges, all the flanges lying in the same vertical plane and defining a window opening, an upwardly opening curved saddle fixed to each side flange adjacent the upper end of the window opening, a screen supporting bar seated in the saddles and extending across between the same in the plane of the window opening, such bar having a rounded lower edge matchingly seated in the curved portions of the saddles, the front face of the bar being substantially parallel with the vertical plane of the window casement and spaced outwardly therefrom, the back face of the bar inclining from the lower curved edge of the bar toward the front face thereof, a flat foot plate connected with and offset inwardly and upwardly from the front face of the bar and engaging the top flange of the casement in face to face relation therewith, a sheet of wire cloth fixed to the bar and extending over the back face thereof and lying against the side flanges of the window casement, and means associated with the casement and the lower end of the screen and effective to place the latter under substantial tension.

DAVID JORDAN RUST.
